UNITED STATES PATENT OFFICE.

ALBERT C. SNELL, OF ROCHESTER, NEW YORK, ASSIGNOR TO ELECTRO SURGICAL INSTRUMENT CO., OF ROCHESTER, NEW YORK, A CORPORATION OF NEW YORK.

TOOL-HOLDER.

1,038,011.

Specification of Letters Patent. Patented Sept. 10, 1912.

Application filed July 28, 1908. Serial No. 445,023.

To all whom it may concern:

Be it known that I, ALBERT C. SNELL, of Rochester, in the county of Monroe and State of New York, have invented certain new and useful Improvements in Tool-Holders; and I do hereby declare the following to be a full, clear, and exact description of the same, reference being had to the accompanying drawings, forming a part of this specification, and to the reference-numerals marked thereon.

The present invention relates to tool holders and it has for an object to provide a construction in which the field of operation of a tool in the holder is perfectly illuminated in order that the operator may clearly see the object operated upon.

To these and other ends the invention consists in certain improvements and combinations of parts all as will be hereinafter more fully described, the novel features being pointed out in the claim at the end of the specification.

In the drawings: Figure 1 is a side view 25 of a tool holder constructed in accordance with this invention; and Figs. 2 and 3 are detail longitudinal sectional views.

In this invention, means carried with the tool projects a beam of light to the field 30 where the tool is to operate. The form of the invention herein shown is particularly designed for the removal of foreign substances from the human eye and when used permits the patient's head to rest comfortably and the operator to shift to a position best suited for the operation. The light is always exactly where the operator wishes it and the help of an assistant to hold a lens is unnecessary. Further the use of a speculum is dispensed with as the operator can hold the patient's eye open with the other hand.

In this embodiment I provide a tool holder 1 of polygonal cross section to permit it to be easily manipulated. At one end of the holder is a chuck 2 of any suitable formation which permits the tool 3 to be removed and replaced by another and also to be adjusted longitudinally so that it may be fixed in any desired position relatively to the beam of light.

Carried by the tool holder is a small illuminator which preferably comprises an electric incandescent lamp bulb 4 removably

fitted in a socket 5 carried by an arm 6 that is branched from the holder 1. Means is provided for projecting rays from the illuminator toward the tool. In this instance, the illuminator has arranged in front of it a condensing lens 7 whose optical axis intersects the longitudinal axis of the tool at a point at or slightly in advance of the end of the tool. By reason of this arrangement of the lens, the tool holder may be turned or shifted to any position without taking the illumination from the field of operation of the tool.

Any suitable means may be employed for establishing electrical connection between the bulb and an electric circuit. In the present instance, the tool holder is made hollow and has an electrical conductor 8 arranged therein and insulated therefrom, one end being connected to a contact 11 within and insulated from the socket 5 after extending through arm 6, and the other end being connected to a terminal 9 which is insulated at 10 from the reduced end 12 of the holder forming the other terminal. The reduced end forms a plug which may be fitted in any suitable socket. The other conductor leading to the bulb embodies the metal of the tool holder, arm 6 and socket 5.

When the tool is used it, of course, must be turned to various positions. The polygonal shape of the holder permits this action and the illuminator is turned with it, causing the illuminated point to be practically the same for every position of the tool. It will be noted that the offset arm projects forward from the forward end of the tool holder and that the lamp bulb and lens are located in proximity to the chuck 2. This arrangement throws the illuminating means forward of the gripping portion of the tool so that the hand of the operator or user cannot become located between the illuminator and the tool, and it is thus possible to maintain the field of operation of the tool constantly illuminated.

A tool constructed in accordance with this invention is inexpensive to manufacture and simple to operate. It is perfectly hygienic as it may be sterilized without affecting its working parts.

What I claim is:

The combination with a tool holder having a tubular handle, a tubular arm extend-

ing upwardly and forwardly from the handle and provided with a lamp socket at its extremity, of a combined incandescent lamp and condensing lens fitted in the socket and disposed at an angle to the holder for illuminating the field of operation of the tool in all positions of adjustment of the

holder, said tubular handle and arm being adapted to receive the conductors for the lamp.

ALBERT C. SNELL.
